UNITED STATES PATENT OFFICE.

OLIVER H. QUERNHEIM AND HECTOR NEUHOFF, JR., OF ST. LOUIS, MISSOURI, ASSIGNORS TO METALLIC SASH-OPERATOR COMPANY CORPORATION, OF ST. LOUIS, MISSOURI, A CORPORATION OF MISSOURI.

WINDOW-SASH OPERATOR.

1,242,889.

Specification of Letters Patent.

Patented Oct. 9, 1917.

Application filed February 23, 1917. Serial No. 150,546.

To all whom it may concern:

Be it known that we, OLIVER H. QUERNHEIM and HECTOR NEUHOFF, Jr., citizens of the United States, and residents of the city 5 of St. Louis, Missouri, have invented a new and useful Window-Sash Operator, of which the following is a specification.

This invention relates to sash operating devices.

10 An object of the invention is to provide an improved sash operating device comprising a longitudinally movable shaft, a rack in connection with the shaft preferably in such manner that the shaft is capable of 15 rocking movements relative to the rack but is held against relative longitudinal movement, actuating devices cooperating with the rack for moving the shaft longitudinally in opposite directions, and stop devices arranged to be operated as an incident to the 20 movement of the shaft the desired distance in either direction to stop the actuating devices and thereby prevent further movement of the shaft which might result in injury 25 or damage to some of the connections.

With the foregoing and other objects in view, we have illustrated a preferred embodiment of the invention in the accompanying drawings, in which—

30 Figure 1 is a plan view of the sash operating device with the sash in closed adjustment.

Fig. 2 is a side elevation thereof.

Fig. 3 is an inner side elevation showing 35 the stop devices.

Fig. 4 is a plan view further illustrating the stop devices.

Fig. 5 is a detailed sectional view on the line 5—5 of Fig. 3, showing the connection 40 between the rack and the axially movable shaft.

The shaft 1 is supported for axial movement in roller bearing devices 2. The rack 3 by which the shaft is to be actuated has 45 upper and lower flanges embracing the shaft between them as illustrated in Fig. 5. Binding clips 4 are employed to attach the rack in connection with the shaft, and abutment collars 5 attached to the shaft at the 50 ends of the rack prevent relative longitudinal movement of the rack and shaft. The shaft is connected to the window sashes by

links 6 which are pivoted to adjustable clamps 7 on the shaft and to brackets 8 on the window sashes. Links 9 connect the 55 links 6 with pivoted brackets 10, so as to provide an efficient, strong and durable toggle connection for actuating the sashes by the axial movement of the shaft.

The rack 3 extends through the case 11 60 of the actuating device and meshes with a pinion 12 within the case. The pinion 12 is in rigid connection with a gear 13 meshing with a worm 14 on a manipulative shaft 15, so that by turning the shaft 15 the gear 65 13 and the pinion 12 will also be turned with the result that the shaft 1 will be moved axially. Any appropriate actuating device for the shaft 15 may be employed and for convenience we have illustrated a 70 crank wheel 16.

The foregoing construction is substantially the same in essential particulars as that disclosed in our Patent No. 1,191,923, dated July 18, 1916. The present invention 75 comprises improvements adapted to be combined with the mechanism above described and with any other similar sash operator.

In the form shown a sleeve 17 is attached to the inner end of the shaft 15 and is provided with two arms or shoulders 18. The case 11 is formed with lugs 19 constituting supports for a stop rod 20. The stop rod 20 is adapted to be moved to position to be engaged by one of the projections 18 and 85 thus prevent further rotation of the shaft 15 in one direction.

A spring arm 21 is attached to the case 11 at 22 and the opposite end of said arm extends through a hole in the rod 20 and 90 normally holds the rod out of the path of movement of the arm 18. A stop member 23 in connection with the rod 20 limits movement of the rod by the spring action of the spring 21. The clip 4, which is on 95 the same side as the spring arm 21, has a projection 24 adapted to engage with the spring arm and actuate the same in opposition to the tension thereof to move the rod 20 into the path of movement of the projection 18 and thus stop the actuating mechanism from further movement in the direction in which it was being operated. The clip 4 is adjustable and may be placed in 100

any position desired in connection with the rack so that adjustments may be made to vary the extent of movement of the shaft 1.

The stop device for stopping the actuating mechanism when being operated in the opposite direction comprises a spring arm 25 secured to the case 11 at 26 and passing through a hole in a stop rod 27 movably supported in lugs 28 in connection with the frame of the actuating mechanism. The spring arm 25 is effective normally to hold the rod 27 out of the path of movement of the other projection 18, but is capable of movement to actuate the rod 27 into the path of movement of said projection. Outward movement of the rod 27 by the spring arm 25 is limited by a stop member 29 in connection with the rod which abuts against one of the supporting lugs 28. Inward movement of the rod 27 is effected by a projection 30 in connection with the clip 4 on the same side of the actuating mechanism as the spring arm 25. The lug 30 engages the arm 25 and actuates the same to move the rod 27 into the path of movement of the projection 18 and thus stop or lock the actuating mechanism from further movement in the direction in which it was being operated.

Since the clip 4 may be adjusted in different positions the extent to which the shaft 1 will be moved may be optionally varied.

The stopping of the actuating mechanism by the rod 20 or rods 27 does not prevent reverse or opposite actuation of the actuating mechanism to move the shaft in the opposite direction. As an incident to such movement of the shaft in the opposite direction, the projections 24 and 30 will be moved out of contact with the spring arms 21 and 25 respectively, thus enabling said arms to actuate the rods 20 and 27 respectively out of the path of movement of the projections 18.

A device of this character automatically stops the actuating mechanism and prevents excessive strains being exerted or thrown upon the connections with the window sashes, or other parts of the device. The extent of movement of the window sashes may be optionally varied by limiting the extent of movement of the shaft 1, which results from setting or adjusting the clips 4 to any desired positions.

We do not restrict ourselves to the specific construction and arrangement shown, but what we claim and desire to secure by Letters Patent of the United States, is:—

1. In a window sash operating device, the combination with a longitudinally movable shaft, a rack in connection with said shaft, mechanism for actuating said rack and thereby said shaft longitudinally, stops for said actuating mechanism, and devices actuated by said rack for setting said stops to stop the actuating mechanism,

2. A window sash operating device, comprising a shaft, a rack in connection with said shaft, actuating mechanism for actuating said rack and thereby said shaft longitudinally, stops for stopping said actuating mechanism, and means for operating said stops to stop the actuating mechanism by the movement of said shaft longitudinally to a predetermined position in either direction. 75

3. The combination with a longitudinally movable shaft, an actuator for moving said shaft longitudinally in either direction, of stop devices for the actuator, and means in connection with the shaft for actuating said stop devices to position to stop the actuating mechanism by the movement of the shaft in either direction. 80

4. The combination with a longitudinally movable shaft, and actuating mechanism for moving the shaft in either direction, of stop rods movable to and from position to stop the actuating mechanism, spring arms normally holding the stop rods out of position to stop said mechanism, and means in connection with the shaft for moving the spring arms as required to move the stop rods to position to stop said mechanism. 85

5. The combination with a longitudinally movable shaft, gearing for moving the shaft longitudinally in opposite directions, and a manipulative shaft for actuating said gearing, of a stop rod movable to and from position to stop said manipulative shaft, and a device actuated by the shaft and gearing for moving said rod to position to stop said shaft. 95

6. In a window sash operator, the combination with a longitudinally movable shaft, gearing for actuating said shaft longitudinally in opposite directions, a manipulative shaft for operating said gearing, and projections in connection with said shaft, of stop rods movable to and from position to be engaged by said projections, spring arms normally holding said rods out of position to be engaged by said projections, and means in connection with the shaft for actuating said spring arms to move said rods to position to be engaged by said projections. 105

7. In a device of the character described, the combination with a longitudinally movable shaft, and manipulative mechanism for actuating said shaft, of stop rods movable to and from position to stop said manipulative mechanism, spring arms normally holding said rods out of position to stop said mechanism, and adjustable devices in connection with said shaft adapted to engage said spring arms and actuate them to move said rods respectively, to position to stop said manipulative mechanism. 115

8. In a device of the character described, the combination with connections from the window sash, a worm shaft for actuating 120

5 said connections, and means for turning said shaft in either direction, of a stop device under control of said connections for stopping said worm shaft when said connections are moved to a desired point of stoppage in either direction.

9. In a device of the character described, the combination with sash operating connections and a revoluble worm shaft for operating said connections in either direction to move the sash, of stop members movable to and from position to stop said shaft, and means for moving said stop members to position to stop said shaft when said connections are moved to desired points of stoppage, and for moving said members to positions to release said shaft when reverse movement of said connections occurs.

10. In a device of the character described, the combination with sash operating connections, and a revoluble worm shaft for actuating said connections, of a stop member movable to and from position to stop said shaft, and means for moving said member to position to stop said shaft when said connections are moved to a desired point of stoppage in one direction and for moving said member to idle position when reverse movement of said connections from said

20 point of stoppage occurs.

11. In a device of the character described, the combination with sash actuating connections, gearing for moving said connections, and a revoluble worm shaft for operating said gearing, of a stop member movable to and from position to stop said worm shaft, and means under control of said connections for moving said member to position to stop said worm shaft when said connections are moved to a desired point of stoppage.

12. In a window sash operating device, the combination with gearing for actuating the sash operating connections, and a revoluble worm shaft for operating said gearing, of a projection in connection with said worm shaft, a stop member movable into and out of engagement with said projection to stop rotation of the worm shaft and to release 50 the same, a spring normally holding said member out of the path of movement of said projection, and means for actuating said member into the path of movement of said projection.

13. In a window sash operating device, the combination with sash operating connections, gearing for actuating said connections to move the sash, and a revoluble worm shaft for operating said gearing, of a projection in connection with said shaft, a stop member movable into and out of the path of movement of said projection to stop and to release said shaft, a spring for actuating and yieldingly holding said member out of the path of movement of said pro-

jection, and a device controlled by said connections for moving said member into the path of movement of said projection when said connections are moved to a desired point of stoppage.

14. In a window sash operating device, the combination with sash operating connections, gearing for actuating said connections to move the sash, and a revoluble worm shaft for actuating said gearing, of a stop member movable to and from position to stop rotation of said worm shaft in one direction, said member being normally out of position to stop said shaft, and means under control of said connections for moving said member to position to stop said worm shaft.

15. In a window sash operating device, the combination with sash operating connections, gearing for actuating said connections, and a worm shaft for operating said gearing, of stop members for said shaft, means normally holding said members out of position to stop said shaft, and means controlled by said connections for moving said members respectively to locking position to stop said shaft from rotation when said connections arrive at desired points of stoppage in either direction.

16. In a device of the character described, the combination with a revoluble shaft, and means for turning said shaft, of a stop member movable to and from position to stop said shaft against rotation, a spring normally holding said member out of position to stop said shaft, and a device actuated by said shaft for moving said member to position to stop said shaft.

17. In a window sash operating device, the combination with a revoluble worm shaft, and means for revolving said shaft, of a stop member for said shaft normally out of position to stop said shaft, and a device actuated by the worm shaft for moving said member to position to stop said shaft to prevent further rotation thereof in the direction in which said shaft was turning.

18. The combination with a rack, gearing for actuating said rack, of a stop member, a support in which said member is movable, and a device actuated by movement of said rack to a desired point of stoppage for moving said member to position to stop said worm shaft.

19. In a device of the character described, the combination with gearing, sash operating connections operated by said gearing, and a worm shaft for operating said gearing, of a stop member for said worm shaft normally out of position to stop said shaft, and devices operated by said sash operating connections for moving said member to position to stop said worm shaft at a predetermined time.

20. A window sash operating device, comprising sash operating connections, and a

worm shaft for operating said connections, in combination with a stop member for said worm shaft normally out of position to stop the same, and devices operated by the sash 5 operating connections for moving said member to position to stop said worm shaft when said connections have moved to a predetermined position.

21. A window sash operating device, comprising sash operating connections, gearing for operating said connections, a worm shaft for operating said gearing, a stop member

for said worm shaft, a spring normally holding said member out of position to stop said shaft, and a device operated by said connections for actuating said spring to move said member to position to stop said shaft when said connections arrive at a predetermined position.

In witness whereof, we have signed this 20 specification.

OLIVER H. QUERNHEIM.
HECTOR NEUHOFF, JR.
